COTTON HANDLING APPARATUS

James P. Turner, Tatum, N. Mex.

Application September 16, 1941, Serial No. 411,069

2 Claims. (Cl. 254—188)

The present invention relates generally to new and useful improvements in cotton handling means and has for its primary object to provide, in a manner as hereinafter set forth, a novel apparatus for hoisting cotton pickers' bags which are full of cotton and dumping said cotton into a trailer, wagon or other vehicle or receptacle.

Another very important object of the invention is to provide a cotton handling apparatus of the aforementioned character comprising a block and fall embodying unique means whereby the bags may be shaken over the vehicle for rapidly and completely emptying said bags.

Still another important object of the invention is to provide a cotton handling apparatus of the character described which is mounted for operation on the wagon or trailer to be loaded and which may be conveniently transferred from one vehicle to another.

Other objects of the invention are to provide a cotton handling apparatus of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification taken in connection with the accompanying drawings wherein like characters of reference designate corresponding parts throughout the several views, and wherein:

Figure 1 is an elevational view, showing an apparatus in accordance with the present invention about to hoist a bag of cotton, the trailer being shown in cross section.

Figure 2 is a top plan view.

Figure 3 is a view in vertical section through the block and fall.

Figure 4 is a view in vertical section through the block and fall, taken substantially on the line 4—4 of Figure 3.

Figure 5 is a view in horizontal section through the block, taken substantially on the line 5—5 of Figure 3.

Figure 6 is a view in vertical section through the mast.

Figure 7 is a view in horizontal section, showing the means for securing the mast in position in the vehicle body, taken substantially on the line 7—7 of Figure 1.

Figure 8 is a plan view of a cotton picker's bag provided with rings in accordance with the present invention.

Referring now to the drawings in detail, it will

be seen that reference numeral 1 designates the box-type body of a trailer, wagon or other vehicle 2. Mounted in one side portion of the body 1, at an intermediate point, is a mast which is designated generally by the reference numeral 3.

The mast 3 comprises a tubular post 4 which is permanently secured in position in the body 1. Toward this end, the tubular post 4 has fixed on its lower end a base 5 which is firmly bolted or otherwise secured to the bottom 6 of the body 1 adjacent one side 7 of said body. The post 4 is further secured in position through the medium of clamps 8 which are mounted on the sides 7 of the body 1.

15 The mast 3 further comprises a plate 9 which is fixed on the upper end of the tubular stationary post 4. Fixed on the plate 9 is an internally threaded cup or socket 10. Threaded into the socket 10 is a sleeve 11. Bearings 12 are provided in the end portions of the sleeve 11 and journaled in said bearings is a removable standard 13. Metallic disks 14 are fixed on the ends of the removable tubular standard 13. Extending through the disks 14 is a rod 15 having nuts 16 threaded on its end portions. The nuts 16 are fixed, as by welding, to the disks 14.

Rotatably mounted on the upper end portion of the tubular standard 13 is a cap 17. Guy wires 18 have one end connected to the cap 17. Mounted on the walls of the vehicle body 1 are eyes 19. The other ends of the wires 18 are detachably connected to the eyes 19 by means including turnbuckles 20 having fixed on one end snap hooks 21 which are engageable with said eyes.

35 Fixed on the rotary tubular standard 13 is a horizontally projecting arm 22 which is provided with a suitable brace structure 23. Mounted on the outer end portion of the arm 22 is a pulley 24. An operating rope 25 has one end connected 40 to the outer end portion of the arm 22. The operating rope 25 passes around a pulley 26 on the side of the vehicle body 1 which is remote from the mast 3, said rope then passing over the pulley 24 from which it depends to a point adjacent the ground. A weight 27 is provided on the free end 45 of the operating rope 25.

Suspended from the arm 22 is a block and fall apparatus which is designated generally by reference numeral 28. The apparatus 28 includes a double block 29 comprising a casing or the like 30 which is secured by a bolt 31 beneath the free end portion of the arm 22. Journaled on a shaft 32 in the casing 30 is a pair of pulleys or sheaves 33. Links 34 are pivotally suspended from the end portions of the casing 30. Pivotally mount-

ed on the lower end portions of the links 34 is a pair of side bars 35. Paralleling the side bars 35 is an intermediate bar 36. Journaled for rocking movement between the intermediate bar 36 and the side bars 35 are rope guides 37 comprising rollers 38. Clamped longitudinally on the side bars 35 and depending therefrom are bumpers 39 the purpose of which will be presently set forth.

The apparatus 28 further includes a fall 40 which is suspended from the block 29 by a hoisting rope 41. The fall 40 includes an inverted hood or casing 42 having journaled on a shaft 43 therein a single pulley or sheave 44. Rising from the end portions of the casing 42 are pivotally mounted links 45. Pivotally mounted on the upper end portions of the links 45 is a frame structure in the form of a pair of parallel bars 46. Rope guides 47, substantially similar to the guides 37, are journaled for rocking movement between the bars 46. Mounted on the bars 46 in spaced relation thereto for engagement with the bumpers 39 are substantially similar bumpers 48. The hoisting rope 41 is trained in the usual manner around the grooved pulleys 33 and 34. A weight 49 is provided on the free end of rope 41.

Suspended by a swivel connection 50 beneath the casing 42 is a pair of plates 51. Pivotally mounted at an intermediate point between the plates 51 is a bar 52. Hooks 53 and 54 extend in opposite directions from one end portion of the bar 52. A trip rope 55 is connected to the other end portion of the bar 52.

A cotton picker's bag is designated by reference numeral 56, said bag being open at both ends. Rings 57 are secured on the ends of the bag 56. A single ring 58 is secured to an intermediate portion of the bag 56. It is thought that the manner in which the apparatus functions will be readily apparent from a consideration of the foregoing. Briefly, the arm 22 is swung outwardly to substantially the position suggested in Figure 1 of the drawings and the fall 40 is lowered. When the fall 40 is lowered in this manner the weight 49 is elevated into engagement with the block 29. Thus, downward movement of the fall 40 is definitely limited and the rope 41 is maintained under the correct tension at all times. The two end rings 57 on the cotton bag 56 are now engaged in the hook 53 and the intermediate ring 58 is engaged on the hook 54. The apparatus 28 is now actuated through the medium of the rope 41 for hoisting the bag of cotton

sufficiently to clear the top of the vehicle body 1. Through the medium of the rope 25 the arm 22 is then swung to position the bag of cotton over the body 1. Then, through the medium of the trip rope 55 the bar 52 is actuated for swinging the hooks 53 and 54 upwardly for causing the rings 57 to slip off of said hook 53. It will thus be seen that the ends of the bag 56 are permitted to fall for discharging the cotton into the body 1. To dislodge any cotton that may remain in the bag, the fall 40 is moved upwardly and downwardly through the medium of the rope 41 in a manner to cause said fall to rapidly strike the block 29, the bumpers 48 engaging the bumpers 39 when this is done. The construction and arrangement of the pivoted links 34 and 45, the bumpers 39 and 48, etc., is such as to cause the bag to be thoroughly shaken when the fall 40 is caused to collide with the block 29. When the bag has been emptied the arm 22 is swung outwardly again, the fall 40 is lowered and the empty bag is removed. By disconnecting the elements 18 and 25 from the body 1 the tubular standard 13 with the apparatus thereon may be expeditiously removed from the post 4 and transferred to a similar post on another vehicle.

It is believed that the many advantages of a cotton handling apparatus constructed in accordance with the present invention will be readily understood and although a preferred embodiment of said apparatus is as illustrated and described, it is to be understood that changes in the details of construction and in the combination and arrangement of parts may be resorted to which will fall within the scope of the invention as claimed.

Having described the invention, what is claimed as new is:

1. A hoist including a block, a fall, a rope operatively connecting said block and said fall, the block and fall each comprising a housing, pairs of links pivotally mounted on each housing, a bar pivotally mounted on each pair of links, a bumper mounted on each bar, and means for detachably connecting a load to the fall.
2. A hoisting block including a casing, pulleys journaled in said casing, pairs of pivoted links suspended from said casing, a horizontal bar pivotally mounted on the lower end portions of each pair of said links, and rockable guides for a hoisting rope journaled between said bars.

JAMES P. TURNER.
